UNITED STATES PATENT OFFICE.

ZACHARY BRONSTEIN, OF MALDEN, MASSACHUSETTS.

SIGN.

Application filed November 20, 1925. Serial No. 70,341.

The invention relates to a sign composed of a collection of individual elements or units certain of which are character-bearing elements, all of which are self-attaching to one another and which combined form any desired indication or sign.

Among the objects of the invention are to provide means whereby the body of the sign composed of a collection of individual elements or units, as explained above, will have a substantially continuous front surface or face and give the effect of a one-piece sign; also, to provide whereby the separate elements or units may be combined to abut one another along sharply defined edges by which a proper and precise alignment of the elements may be obtained during the assembly of the elements in forming the sign.

The invention can best be seen and understood by reference to the drawings in which—

Figure 1 is a front elevation of the sign.
Fig. 2 is a rear elevation.

Fig. 3 is a front elevation of one of the elements entering into the formation of the sign.

Fig. 4 is a rear elevation of the element shown in Fig. 3.

Fig. 5 is a section on the line 5—5 of Fig. 2, and

Fig. 6 is a rear elevation of one of the elements at the end of the sign.

Referring to the drawings:—

1 represents the sign. 2 represents the individual elements or units of which the sign is composed and which are self-attaching to one another to form collectively the complete sign, each of the elements excepting preferably those elements at the opposite ends of the sign and excepting, also, space-forming elements, if such are employed, bear some character, as for example a letter, and which letters collectively, when the elements or units are fastened together, form the matter indicated by the sign as a word or words.

Each of the elements 2 comprises a body 3 preferably of metal plate and square or rectangular in form. The body is provided on its opposite sides with very sharply defined edges 4 and 5 respectively preferably obtained by cross-cutting the metal. At its top and bottom the body of the element is provided with extensions 6 and 7 respectively turned to extend over the body at the back and form flanges with sockets beneath

said flanges between them and the body. Projecting laterally from the respective flanges are tongues 8 and 9 respectively. These tongues have extension beyond the adjacent side edge 5 of the body and are turned or bent preferably at points 10 just adjacent said edge so that the tongues will lie substantially in the same plane with the sockets formed between the flanges and the body of the element as aforesaid.

In combining the elements or units the tongues 8 and 9 projecting from the flanges of one element are inserted in sockets formed by the flanges of the next adjacent element 70 and the two elements pushed together until their adjacent side edges contact with one another. Owing to the depression of the tongues the front surfaces or faces of the several elements will lie substantially flush 75 with one another while the abutting edges of the respective elements will fit squarely against one another when the elements are properly aligned, and form a practically continuous front surface or face for the 80 combined elements.

In order to retain the elements in place each of the tongues on any one element is provided with a projecting nib or boss 11 which, when the tongue of the one element is inserted into the socket formed by the flanges of the adjacent element will spring these flanges slightly owing to the elasticity of the metal and, when the elements are properly combined, will fit into holes 12 cut 90 in the flanges. By this means the elements are securely fastened together, but in a manner permitting of their being disconnected when forcibly pulled apart. I prefer, also, that all the elements composing the sign be severally attached or nailed to the base (not shown) upon which the sign is arranged. To this end all the tongues of the respective elements are provided with nail holes 13. In the assembling of the elements nails are driven into the base through the holes 13 in the tongues for attaching any one element after this element has been properly positioned and before the attachment of the next adjacent element. At the opposite ends 95 of the sign the end elements or units are preferably provided with openings 14 in them through which screws are inserted and screwed into the base.

All the elements are preferably formed 110 from blanks by striking up the metal. The characters or letters on the character-bear-

ing elements are also preferably struck from the metal although they may be formed thereon in any desired manner.

In practice it is the purpose to provide a 5 large number of individual elements including character-bearing elements, space-forming elements and elements for the ends of the sign or end pieces. From these elements such are chosen as will when combined form 10 any desired indication or sign.

Having thus fully described my invention, I claim and desire to secure by Letters Patent of the United States:—

A sign comprising a number of individual 15 character-bearing elements, each of said elements comprising a body on which the character is displayed and which body is pro-

vided on its opposite sides with free edges, said body having also, at its top and bottom, extensions turned to extend over said body 20 at the back and form flanges with sockets beneath said flanges between them and the body, said flanges being provided with tongues projecting laterally therefrom with extension beyond the adjacent side edge of the body, said tongues being turned to lie in substantially the same plane with said sockets whereby the tongues extending from the flanges on one element will enter the sockets and be retained by the flanges of an 25 adjacent element when said elements are brought together with edges abutting.

ZACHARY BRONSTEIN.
